UNITED STATES PATENT OFFICE.

EMERSON C. EACHEL, OF MONTCLAIR, NEW JERSEY, ASSIGNEE, BY MESNE ASSIGNMENTS, TO UNDERWOOD COMPUTING MACHINE COMPANY, OF NEW YORK, N. Y., A CORPORATION OF NEW YORK.

COMBINED TYPE-WRITING AND COMPUTING MACHINE.

1,269,797.

Specification of Letters Patent. Patented June 18, 1918.

Application filed August 19, 1911. Serial No. 644,959.

To all whom it may concern:

Be it known that I, EMERSON C. EACHEL, a citizen of the United States, residing in Montclair, in the county of Essex and State of New Jersey, have invented certain new and useful Improvements in Combined Type-Writing and Computing Machines, of which the following is a specification.

This invention relates to combined type-writing and computing machines, in which the numeral keys set up pins which are subsequently used in determining the extent of rotation of a set of dial wheels; said wheels being turned by means of an electric or other motor.

The invention relates particularly to the means for causing the motor to operate the dial wheels or devices.

One of the leading features of the invention consists in controlling the connections between the dial wheels and the motor by means of the tabulator keys which govern the movements of the typewriter carriage, so that after the numeral keys have been operated to set up said pins and write the corresponding numbers on the work sheet, the manipulation of any tabulator key will cause connection to be established between the motor and the dial wheels, so that the number previously set up is carried into said wheels.

The invention is of great advantage in performing certain kinds of computation. In performing many kinds of work, the tabulator keys are in almost constant use, so that the operator needs only to manipulate the typewriter in the ordinary way, without giving much, if any, attention to the matter of carrying numbers into the dial wheels after setting them up. By keeping in mind always to use the tabulator keys for positioning the typewriter carriage, the necessity of attending to the operation of the dial wheels is avoided.

I connect to said tabulator keys means for closing a clutch between the electric motor and the general operator provided in the computing mechanism for rotating said dial wheels. I also preferably cause said tabulating keys to close a circuit through the motor, the latter rotating intermittently as required. Other features and advantages will hereinafter appear.

In the accompanying drawings,

Figure 1 is a longitudinal sectional eleva-

tion of a combined adding and typewriting machine of the Underwood-Hanson type, showing the present improvements applied thereto.

Fig. 2 is a sectional side elevation of the circuit and clutch-closing members, showing them in normal positions.

Fig. 3 is a side elevation of a pair of brushes and the device upon which they are mounted.

Fig. 4 is a perspective view of a disk, which is used for supporting and operating a rotary bridge.

Fig. 5 is a perspective view similar to Fig. 2, but showing the latch withdrawn and the circuit closed.

Fig. 6 is a sectional front elevation through the clutch mechanism, which is arranged below the frame of the computing mechanism.

Fig. 7 is a side elevation, showing a tabulator key and associated mechanism, the parts being in normal position.

Fig. 8 is a front view of the tabulator keys and connections.

An intermittently operated electric or other motor 1 is provided with a main shaft 3.

A rack 13, forming part of a rack frame, is movable forwardly and backwardly in the base of the adding machine, and performs the final portion of the computing operation. This rack frame is reciprocated intermittently by the constantly rotating shaft 3, by means of a clutch mechanism; 85 said rack frame being connected to a crank shaft to be driven thereby, and the crank shaft being connected by a worm gearing to said shaft 3, as will presently be set forth. Said clutch mechanism may be substantially 90 identical with that shown in the patent to Thornton, 1,146,371, dated July 13, 1915.

Upon the rack frame is secured a yoke or carrier 14, in engagement with which is the upper end of an arm 15, provided on a cross head 16, which moves forwardly and backwardly, or from left to right at Fig. 1, so as to reciprocate said rack frame 13; said cross head being carried on a horizontal slide 17, which works in bearings 18 on a 100 casing 19. This slide is reciprocated by means of a crank 23, fixed on a horizontal shaft 24; said crank carrying a slide block 26, working in a groove 27 in the cross head.

Loose on shaft 24 is a worm gear 30 110

meshing with a worm 31, the latter fixed on shaft 3, so that the worm gear or wheel 30 may be intermittently rotated.

Fixed to crank shaft 24 is a cupped member 32 of a clutch. The hub of worm gear 30 is designated as 33. The clutch also comprises gripping rolls 34 to run upon opposite sides of the gear wheel hub 33, Fig. 2. These rolls normally occupy pockets 35 in

10 the clutch cup, said pockets having inclined walls against which the rolls may wedge, although the rolls are normally released.

The clutch rolls are shiftable between gripping and releasing positions in the 15 pockets 35 by means of a ring 36 fitted upon the gear hub 33 to be independently rotatable and occupying a position within the cup 32. This ring 36 has cutaways or recesses 36^a to receive loosely the rolls 34, so 20 as to control the latter. The roll-controlling ring 36 is frictionally connected to the gear hub 33 by means of a double spring 37 secured to the ring by a screw 37^a and pressing pins 37^b through perforations in the ring 36 25 against the surface of gear hub 33. The hub takes a grip upon the ring, so that the latter always tends to rotate with the hub. This tendency is in a direction to close the clutch. Normally said ring 36 is restrained from 30 causing the rolls to bind; or in other words said ring is normally held in clutch-releasing position.

For this purpose there is provided a trip pin or latch 40 normally in the path of a 35 lug 41 provided upon the releasing ring 36, said lug 41 projecting through an opening 41^a in the clutch cup 32. Whenever the crank shaft 24 is to be clutched to the gear 30, the latch 40 is raised to release the lug 41 to permit the gear hub 33 (assuming the latter to be rotating) to carry around both the ring 36 and the rolls 34 until the latter grip upon the inclined walls of the pockets 35, thereby closing the clutch. The pin 40 is 40 immediately dropped again into the path of lug 41, so that at the completion of a single revolution of the shaft 24, the latter is again unclutched automatically from the worm gear 30. The latch 40 is also employed for 45 the purpose of controlling the motor circuit, closing said circuit, and then opening the same. The circuit is closed by the upward movement of the latch 40, which withdraws it from the path of the clutch-releasing lug 41. When said latch 40 is lifted, a spring 42 in said lug, by pressing against an ear 43 on a disk 44, Fig. 4, imparts to the latter a slight advance rotation; said disk 44 being, for convenience, loosely mounted 50 upon the hub 45 of the clutch ring 32, Fig. 5.

This starting forward of said disk 44 is utilized for the purpose of closing the circuit through the motor 1. Upon said disk 55 44 is carried a circular or disk-like bridge

46, and against the outer face of 46 press yielding brushes or contacts 47, 48 secured upon a disk-like support 49 of insulating material and connected by arms 50 to conductors 51, the latter directly connected with the motor 1. The tip 52 of the finger 48 rests normally upon an insulating lug 53 filling the recess 54 in the annular bridge 46; while the other finger 47 is constantly in contact with said bridge, being so short 75 as to escape said recess 54. The bridge 46 is secured by screws 55 upon the outer face of an insulating disk 56, as set forth in said Thornton patent. The members 44, 56 and 46 are rigidly secured together. When the 80 spring 42 moves the bridge disk 44 from the normal position at Fig. 2 to the position at Fig. 5, the tip 52 of contact 48 stands in contact with the bridge 46, so that a circuit is completed through the latter, and 85 through the brush or contact to the motor.

The revolution of the motor turns the clutch-controlling ring 36 to cause the rolls 44 to bind the gear hub 33 to the clutch ring 32; and all of these members rotate 90 together until a complete revolution is effected of the gear 30.

In the meantime the latch pin 40 is dropped into the path of the ear 43, and arrests the latter when the tip 52 is resting 95 upon the insulating plug 53, and hence the motor circuit is broken. The motor however continues to revolve by means of its momentum, and through the friction plugs 37^b causes the clutch ring 36 to complete its 100 revolution to the Fig. 2 position, thereby compressing the spring 42. At the same time, all of the parts are brought to their normal Fig. 2 positions, the rolls 34 becoming unclutched from the cup 32 substantially 105 as shown.

The rack frame 13 is caused to reciprocate after the numeral keys of the typewriter have been operated to set up a number. This rack frame operates to turn the computing 110 wheels to different extents, depending upon the key operated. There is shown a special key to operate said clutch, and cause a reciprocation of the rack frame, this special key being substantially the same as shown in 115 pending application No. 607,925, filed February 11, 1911, and in said Thornton patent. Said key is designated as 57, and is mounted on a stem 58 pivoted at its lower end to a lever 59 fulcrumed at 60 upon the machine frame. Said lever in turn, depresses a cross lever 61 which is pivoted at 62 to the framework, and at its other end engages a notch 63 formed in the top of the trip pin or latch 40, so as to cause and control the movements 125 of said latch.

Depression of the key 57 carries down the lever 59; the latter rocks the lever 61 about its fulcrum 62, the other end of the lever lifting the latch 40 away from the clutch 130

dog 41 and the bridge ear 43. The operator then immediately releases the key 57, which is returned to normal position by a spring 69. The lever 61 has a returning spring 62^a.

- 5 The typewriter has the usual set of type-operating keys, including alphabet keys and also including numeral keys 88 mounted on levers 88^a and connected by bell cranks 89 to type bars 90, which are thrown back 10 against a platen 91 mounted on a carriage 92. The carriage is power-driven, and has a rack 87 meshing with a pinion 86, connected with an escapement wheel 85, the latter controlled by dogs 84, operated by a universal bar 83, which is actuated by the type bars, so that whenever any type key is actuated, the carriage 92 is caused to feed a letter space.

Fastened at the back of the carriage 92, 20 are brackets 93, carrying a rack 94, to receive adjustable cams or tappets 95. Whenever any tappet, during the travel of the carriage, passes beneath the set of jacks 96, it raises the forward ends of the jacks in 25 succession, turning each on its pivot 97, and depressing its rear end to press down the corresponding one of a set of wires 98. These wires are connected at their lower ends to levers 99 on a fulcrum rod 100.

- 30 Each lever 99 raises one of a set of linkages 101, each linkage having a pin 102 to lift the rear end of a rack 103, the forward end of which meshes with a pinion 104, connected to a computing wheel or dial 105. 35 Each rack carries a set of pins 106, and one of these is depressed by the operated type key 88; each key having a stem 110, for this purpose, to depress a crank 112, fast to a shaft 113, which is connected to a linkage 40 114, to depress one of the pins 106 upon the lifted rack bar 103; there being one linkage 114 for each key, each linkage being in position to depress a corresponding pin 106 on which ever rack bar is lifted, as set forth in 45 said application. After the keys 88 are manipulated to write a number, and the corresponding racks 103 accordingly elevated as the paper carriage feeds along, and certain pins 106 thereon depressed, thus temporarily 50 registering a number on said pins, there is caused a reciprocation of the rack frame 13 to carry the registered numbers into the dial wheels 105. This frame 13 usually includes a pair of arms 115 connected by a 55 transverse horizontal bar 116, which is in position to engage all the displaced pins 106, and to give corresponding forward endwise movements to their racks 103, thereby turning the dial wheels 105 accordingly; the return movements of the racks not turning said wheels, however, because of a pawl-and-ratchet connection (not shown) between said wheels and their drive pinions 104. 60 Pinions 116^a meshing with racks 13, are 65 also in mesh with segments 116^b fixed on

rock shaft 116^c, and when the slide 15 is disconnected from the yoke 14 said general operator may be operated manually by a handle on said rock shaft 116^c.

The tabulating mechanism usually employed on the Underwood typewriter, comprises a series of independently operable keys 120, arranged at the front of the typewriting machine on the forward ends of levers 121, the latter pivoted at 122 and connected at their rear ends to upstanding decimal stop rods 123, any of which may be lifted by its key to engage a column stop 124 on said paper carriage. Each column stop rod 123 has a lug 125, and any of these lugs may operate a lever 126, connected by a link 127 to a releasing lever 128, the latter adapted to lift the carriage rack 87 from the pinion 86.

Beneath the forward ends of the tabulating key levers 121, extends a horizontal transverse universal bar 129, depressible by any of the tabulating keys 120, said bar 129 mounted on the forward ends of a pair of arms 130, 131, rigidly connected by a rock shaft 132 extending across the machine, and journaled in the framework. A spring 133 holds up the universal bar.

Upon depression of any of the tabulating keys 120, said universal bar 129 is depressed, and a finger 134 on one end thereof bears down upon an arm 135, mounted upon said stem 58, so as to carry down said stem and release the latch 40, thereby closing the circuit through the motor, and clutching the motor to the general operator 13. The operator releases the key 120, preferably after the carriage has completed its run, or before the completion of the cycle of movements of the operator 13, so that the latch 40 is returned to normal position, and intercepts the ear 43 and the dog 41. Hence when any tabulating key is depressed, it effects not only the tabulating operation, but also an operation of the general operator 13.

When it is desired to silence the tabulating keys in respect to the latch 40, so that said keys may be operated without affecting the motor or the clutch, the arm 135 may be swung down from the position at Fig. 7, so that it cannot be reached by the finger 134 upon the universal bar 129.

A detent 136 is fixed to the arm 135, which is pivoted at 137 to the stem 58; said detent having a pin 138 which may be sprung into either of two holes 139 on said stem.

By having a plurality of tappets or cams 95, as described above, it is possible to do cross-adding with a single totalizer. All that is necessary is to have one of said tappets 95 for every column in which it is desired to compute in the totalizer, and the denominational tabulating keys 120 may successively position the carriage in these various columns. In ordinary machines it is

necessary to press the adding key 57 after writing in each column. Where there are five or six columns of figures, as is not infrequently the case, it is not unusual for the 5 operator to forget to press the key 57 after writing the figures in one column. This sometimes inextricably confuses the computation. The present invention does away entirely with the confusion resulting from 10 forgetting to press said key, for the tabulating keys do its work.

Variations may be resorted to within the scope of the invention, and portions of the improvements may be used without others.

15 Having thus described my invention, I claim:

1. The combination with a set of number wheels, a set of numeral keys, a traveling carriage controlled by said keys, means operated by said keys for setting up the digits of a number to be computed, and a general operator for running into the number wheels the number so set up; of a series of tabulating keys for positioning the carriage 25 variably, power-driven means for causing the operation of the general operator, means operated by the tabulator keys for controlling the operation of said power-driven means, whereby the operation of tabulating the carriage effects the computation of a previously set up number, and means shiftable to effect disconnection at will between said tabulator keys and said power-driven means, to permit the operation of 30 tabulating without affecting the general operator.

2. In a typewriting and adding machine provided with a carriage and tabulating mechanism for positioning said carriage to 40 select the printing and computing column, and a keyboard including a set of independently-operable tabulating keys and a special key, the combination with temporary registering devices, a general operator, and a set 45 of computing wheels rotatable by said general operator to variable extents determined by the numbers registered, of an electric motor, a normally open circuit including said electric motor, a normally open clutch 50 between said motor and said operator, and means operable by any of said keys for controlling the closing of said circuit and said clutch, said means settable to hold said tabulating keys ineffective on said circuit and 55 clutch-controlling mechanism, and said keyboard also including numeral keys for printing and setting said registering devices.

3. The combination with a set of number wheels, a set of numeral keys, a traveling 60 carriage controlled by said keys, means operated by said keys for setting up the digits of a number to be computed, and a general operator for running into the number wheels the number so set up; of a series of tabulator 65 keys for positioning the carriage variably,

power-driven means for causing the operation of the general operator, a separate key having means for controlling said power-driven means, said separate key having an arm, and a universal bar operated by the tabulator keys and having a part to engage 70 said arm to control the operation of said power-driven means, whereby the operation of tabulating the carriage effects the computation of a previously set up number, and 75 said arm being shiftable on said special key to a position of disuse; provision being made to hold said arm in either position to which it is shifted.

4. In a combined typewriting and computing machine, the combination with numeral wheels and key-operated type, of a traveling carriage, tabulating keys for positioning said carriage, a device in which numbers are temporarily registered, a lever for causing numbers registered in said device to be carried 80 into the numeral wheels, and a universal bar operated by said tabulating keys for causing the operation of said lever.

5. In a combined typewriting and computing machine, the combination with numeral wheels and key-operated type, of a traveling carriage, a device in which the numbers written are registered, a lever for causing numbers so registered to be carried 85 into the numeral wheels, tabulating keys for positioning said carriage, a universal bar moved by each tabulating key, and means for connecting said universal bar to said lever at will. 90

6. In a combined typewriting and computing machine, the combination with numeral wheels and key-operated type, of a traveling carriage, a device in which numbers are temporarily registered when written, a lever for causing said numbers to be carried into said wheels, tabulating keys for positioning said carriage, a universal bar arranged to be moved by the operation of any tabulating key, and an arm on said lever 100 arranged to be moved into the path of said universal bar to cause said tabulating keys to connect said device to said numeral wheel. 105

7. In a combined typewriting and computing machine, the combination with numeral wheels and key-operated type, of a traveling carriage, a device in which numbers are temporarily registered when written, a lever for causing said numbers to be carried into said wheels, tabulating keys for positioning said carriage, a universal bar arranged to be moved by the operation of any tabulating key, a rock-shaft pivoted on the frame of the typewriting machine, arms fast on said rock shaft supporting said universal bar under said tabulating key, and an arm on said lever arranged 110 to be moved into the path of said universal bar to cause said tabulating keys to connect said device to said numeral wheel. 115

120

8. In a combined typewriting and computing machine, the combination with numeral wheels, keys and printing type, of a traveling carriage, tabulating keys for positioning said carriage, a device in which numbers are temporarily registered, power driven means for carrying the numbers registered in said device into the numeral wheels, a universal bar operated by said tabulating keys, and means controlled by the universal bar for connecting the power driven means to said device.
9. In a combined typewriting and computing machine, the combination with numeral wheels, keys and printing type, of a traveling carriage, tabulating keys for positioning said carriage, a motor control key for completing the computation, a universal bar operated by said tabulating keys, and means for connecting at will said universal bar to said motor control key, so that the latter will be operated thereby.
10. In a combined typewriting and computing machine, the combination with numeral wheels, keys and printing type, of a traveling carriage, a device in which numbers are temporarily set up by said keys, a key for moving the carriage to a position in which to write a new number, a general operator for carrying the numbers set up in said device into said wheels, a motor for driving said general operator, and means operated by said positioning key for causing said motor to drive said general operator.
11. In a typewriting and adding machine provided with a carriage and tabulating mechanism for positioning said carriage to select the printing and computing column, and a keyboard including a set of independently-operable tabulating keys and a special key, the combination with temporary registering devices, a general operator, and a set of computing wheels rotatable by said general operator to variable extents determined by the number registered, of a motor drive, means for controlling said motor drive and connections for enabling said keys to operate, said controlling means, said connections settable to render said tabulating keys ineffective thereon, while said special key remains effective to control said motor drive.
12. In a combined typewriting and computing machine, the combination with a traveling typewriter carriage, and a computing mechanism inclusive of indexing devices and a single set of numeral keys, of a motor for said computing mechanism, a clutch between said motor and said computing mechanism, a circuit for driving said motor, a circuit-closer for said circuit form-
- ing part of said clutch, a group of keys including a tabulating and a special key for closing said clutch, and means under the control of any one of said last-named group of keys for starting said motor to cause the indexed number to be computed.
13. The combination with a set of number wheels, a set of numeral keys, a traveling carriage controlled by said keys, means operated by said keys for setting up the digits of a number to be computed, and a general operator for running into the number wheels the number so set up; of a series of tabulating keys for positioning the carriage variably, power-driven means for causing the operation of the general operator, and means operated by the tabulator keys for controlling the operation of said power-driven means, whereby the operation of tabulating the carriage effects the computation of a previously set up number.
14. In a computing machine, the combination with a traveling carriage, and a key for positioning the same; of computing mechanism; a motor for driving said mechanism; and connections between said key and said motor for starting the latter at the depression of the former.
15. In a computing machine, the combination with a traveling carriage, and a key for positioning the same; of computing mechanism; a motor for driving said mechanism; a starting bar for said motor; and a member operated by said positioning key, consequent upon its depression, for depressing said starting bar.
16. In a computing machine, the combination with a traveling carriage, and a key for positioning the same; of computing mechanism; a motor for driving said mechanism; connections between said key and said motor for starting the latter at the depression of the former; means for rendering said connections inoperative, whereby said motor is rendered uncontrollable by said key; and a special key whereby the motor may be controlled at all times.
17. In a computing machine, the combination with a traveling carriage, and a key for positioning the same; of computing mechanism; a motor for driving said mechanism; a starting bar for said motor; a member operated by said positioning key, consequent upon its depression, for depressing said starting bar; and means connected to move said member into or out of position to depress said starting bar.

EMERSON C. EACHEL.
